[57] CLAIM

The ornamental design of a fishing rod handle, as shown
and described.

DESCRIPTION

FIG. 1 is a top, front and left side perspective view of a
fishing rod handle, showing our new design;

FIG. 2 is a left side elevational view, the right side being
a mirror image thereof;

FIG. 3 is a top plan view thereof;

FIG. 4 is a front elevational view thereof;

FIG. 5 is a rear elevational view thereof; and,

FIG. 6 is a bottom plan view thereof.
